UNITED STATES PATENT OFFICE.

RICHARD WEBB BURNETT, OF MONTREAL, QUEBEC, CANADA.

SPRING STRUCTURE FOR RAILWAY-CAR TRUCKS.

1,117,780.

Specification of Letters Patent.

Patented Nov. 17, 1914.

Application filed February 19, 1914. Serial No. 819,745.

To all whom it may concern:

Be it known that I, RICHARD WEBB BURNETT, a citizen of the United States of America, residing in the city of Montreal, Province of Quebec, Dominion of Canada, have invented certain new and useful Improvements in Spring Structures for Railway-Car Trucks; and I do hereby declare that the following is a full, clear, and exact 10 description of the same.

My invention relates more particularly to the construction of the journal-boxes and the portions of the truck frame immediately contiguous thereto, and it has for its object 15 to simplify equalizer mechanism.

The invention may be said briefly to consist in the construction of the journal-boxes with an extended spring-seat to accommodate all the springs usually seated upon the 20 equalizer bars, the upper ends of the springs according to my invention bearing within the side-sills which are made hollow for the purpose of acting upon the underside of the top thereof. The usual equalizer bars are 25 dispensed with.

For full comprehension, however, of my invention reference must be had to the accompanying drawings forming a part of this specification in which similar reference 30 characters indicate the same parts, and wherein:

Figure 1 is a side elevation partly in section of a truck constructed according to my invention; Fig. 2 is a vertical sectional view 35 thereof taken on line A A Fig. 1 and looking in the direction indicated; Fig. 3 is a vertical sectional view taken on line B B Fig. 2 and looking in the direction indicated; and Fig. 4 is a detail perspective view 40 of the journal-boxes removed.

The truck in the main may be of usual construction with side-sills each consisting of a pair of channel-irons *b* arranged with their flanges toward each other, such side-sills having their component parts united together and the sills themselves being united by transoms *2*, gusset-plates *3*, and other parts common to the construction of railway trucks, and forming no part of my invention. 50

According to my invention the journal-boxes indicated at *c* are cast or otherwise provided with an extended spring-seat *d* consisting preferably of a base of sufficient 55 length to accommodate say for instance three coiled springs indicated at *e*, such seat

being disposed in alignment with and preferably directly beneath the side-sill the portions of the bottom flanges coinciding with this seat being cut away as at *f*. The springs *d* rest upon the spring-seat *d* and extend upwardly into the side-sills through the openings *f* and are borne upon by spring-seats consisting of plate *g* equal in length and breadth to spring-seats *d* and preferably secured to the top of the interior of the side-sills. A pair of pedestal-plates *h* are secured to the sides of the side-sills and have horizontal extensions *m* extending along and strengthening the side-sills and the usual 60 downwardly extending horns *n* straddling the journal-boxes and acting as guides for the extended ends *d'* of the spring-seats *d*. A tie-bar *k* unites the pedestals and strengthens the side of the trucks. 65

A spring-plank *4* is supported as usual from the frame by hangers *5* and in turn supports coiled springs *6* and usual bolster *7*.

As will be seen from the foregoing and so the drawings the truck thus constructed to embody my improved extended spring-seat *g* upon the journal-boxes, when provided with springs and assembled with channel-irons, side-sills specially constructed and 70 combined with pedestal plates as described, dispenses with the use of equalizer bars and affords equal elasticity and strength in the truck.

What I claim is as follows:—

1. In a railway car truck the combination with a hollow side-sill having an opening in its lower side, of a journal-box having an extended spring-seat thereon disposed in alignment with and beneath the side-sill, 75 springs between the spring-seat and the underside of the top of the side-sill and means for guiding the journal-box and protruding ends of the spring-seat thereof in their movement with relation to the side-sill. 80

2. In a railway car truck the combination with a hollow side-sill consisting of a pair of channel-irons arranged with their flanges toward each other and having a portion of their lower flanges cut away to form an opening in its lower side, of a journal-box having an extended spring-seat thereon disposed in alignment with and beneath the side-sill, springs between the spring-seat and the underside of the top of the side-sill and pedestal plates secured to the side of the side-sills and having their horns straddling 85 90 95 100 105 110

the journal-boxes for guiding the journal-boxes and protruding ends of the spring-seat thereon in their movement with relation to the side-sill.

3. In a railway car truck the combination with a hollow side-sill having an opening in its lower side, of a journal-box having an extended spring-seat thereon disposed in alinement with and beneath the side-sills, a spring-seat within the side-sill and consisting of a plate secured to the underside of the top thereof, springs between the spring-seat upon the journal-box and the spring-seat within the side-sill, and means for guiding the journal-boxes and protruding ends of the spring-seat thereon in their movement with relation to the side-sill.

4. In a railway car truck the combination with a hollow side-sill consisting of a pair of channel-irons arranged with their flanges toward each other and having a portion of their lower flanges cut away to form

an opening in its lower side, of a journal-box having an extended spring-seat thereon disposed in alinement with and beneath the side-sill, a spring-seat within the side-sill and consisting of a plate secured to the underside of the top thereof, springs between the spring-seat upon the journal-box and the spring-seat within the side-sill and pedestal plates secured to the side of the side-sills and having their horns straddling the journal-box for guiding the journal-box and protruding ends of the spring-seat thereon in their movement with relation to the side-sill.

In testimony whereof I have signed my name to this specification in the presence of two witnesses.

RICHARD WEBB BURNETT.
